FORK OR SIMILAR ARTICLE

Alfred Dalessandro, New York, N. Y.

Application December 28, 1953, Serial No. 28,242

Term of patent 7 years

(Cl. D44—29)

To all whom it may concern:

Be it known that I, Alfred Dalessandro, a citizen of the United States and a resident of New York city, in the county of the Bronx and State of New York, have invented a new, original, and ornamental Design for a Fork or Similar Article, of which the following is a specification, reference being had to the accompanying drawing, forming a part thereof.

Fig. 1 is a side elevational view illustrating my new design for a fork or similar article.

Fig. 2 is a top plan view thereof.

Fig. 3 is an elevational view of the side opposite that shown in Fig. 1; and

Fig. 4 is an end elevational view thereof.

In the drawing the dominant features of the design reside in the portions shown in full lines.

I claim:

The ornamental design for a fork or similar article, as shown and described.
